UNITED STATES PATENT OFFICE.

CHARLES H. BOECK, OF JACKSON, MICHIGAN, ASSIGNOR TO HUGH L. SMITH,
OF SAME PLACE.

DESIGN FOR A STOVE.

SPECIFICATION forming part of Design No. 22,709, dated August 15, 1893.

Application filed May 31, 1893. Serial No. 476,148. Term of patent 3½ years.

To all whom it may concern:

Be it known that I, CHARLES H. BOECK, a citizen of the United States, residing at Jackson, in the county of Jackson and State of Michigan, have invented and produced a new and original Design for an Oil-Stove, of which the following is a specification, reference being had therein to the accompanying drawings.

Figure 1, is a front elevation of a stove embodying my design. Fig. 2 is a side elevation thereof.

The design consists in the ornamental front A, with swell B, which has the fanciful cap C. At the sides or edges of the front are the curved wings E which have rounded fanciful ends F. At the base of the front of the stove is the fanciful edging H, and the ornamental legs G. At the top of the front of the stove is the cresting D, of the ornamental design shown.

The leading features of the design are the front, and the cresting as shown.

What I claim is—

1. The design for a stove substantially as shown and described. 25
2. In a design for a stove, the design for the cresting substantially as shown and described.
3. In a design for a stove, the design for the front substantially as shown and described. 30

In testimony whereof I affix my signature in presence of two witnesses.

CHARLES H. BOECK.

Witnesses:

M. B. O'DOGHERTY,
A. L. HOBIE.
